UNITED STATES PATENT OFFICE.

CHARLES D. FILSTEAD, OF LOS ANGELES, CALIFORNIA, ASSIGNOR OF TWO-THIRDS TO
SAMUEL B. HAMPTON, OF CORONA, CALIFORNIA.

ORCHARD-HEATER.

1,110,539.

Specification of Letters Patent.

Patented Sept. 15, 1914.

Application filed October 29, 1913. Serial No. 798,024.

To all whom it may concern:

Be it known that I, CHARLES D. FILSTEAD, a citizen of the United States, residing at Los Angeles, in the county of Los Angeles, State of California, have invented new and useful Improvements in Orchard-Heaters, of which the following is a specification.

The invention relates broadly to oil burning orchard heaters and specifically to an improved burner stack with damper for such heaters and of a diffusing draft partition.

The primary object of the invention is to provide an orchard heater of the oil burning type with a combined burner stack and damper affording a means of limiting the vapor or volatile gases arising from the burning oil in the container outside the burner stack together with the air passing into the burner stack, thereby regulating the degree of combustion.

A further object of the invention is to provide partitions with a plurality of openings, concentric with, or adjacent to the sides adapted to fit within the container extending downward into the receptacle and in front of the draft opening with a space between the walls of the receptacle and the partitions so that the air entering from without the receptacle will be diffused in passing through the apertures of the partitions thereby perfectly mixing with the vapor or gases within the container.

A still further object contemplated in the invention, is to provide partitions with a plurality of openings concentric with or parallel to the walls of the container, adapted to fit within this container and extending below the cover and within the container and opposite the draft openings of the receptacle with a space between the walls and the partitions whereby the air from without the receptacle is diffused downward to the oil surface within the receptacle, intensifying the draft at the surface of the oil and permitting the complete burning of inferior grades of oil, no objectionable residue being left.

A still further object of the invention relates to a plurality of openings in the stack above the aperture of the cover of the container which can be brought into or out of register with a corresponding plurality of openings in a sleeve, thus regulating the amount of air entering into the stack and

thereby providing the proper amount of oxygen for complete combustion.

In the drawings accompanying this specification: Figure 1 is a central vertical longitudinal section through the improved orchard heater, showing a tapered stack and sleeve with their openings registering. Fig. 2 is a transverse section on the line 2-2 of Fig 1, viewed in the direction indicated by the arrows, showing the relation of the apertures in the two tapered flues. Fig. 3 is a detail vertical section of a modification of the damper in which the stack is divided into two parts, the upper part being immovable and the lower part being movable. Fig. 4 is an elevation partly in section of a modified form of heater showing a cylindrical receptacle within which is secured a cylindrical shield provided with draft openings. Fig. 5 is a perspective view of the rectangular form of receptacle with the cover removed, showing the method of introducing the partitions therefor, provided with draft openings.

More specifically in the drawings 5 designates a receptacle preferably formed out of sheet metal and pressed into an elongated form of rectangular cross section, having the side walls 6 in which are disposed a series of air entrance apertures 7 which are preferably placed near the top edge of the walls, the end walls 8 and 9 also being provided with openings 10.

The receptacle is adapted to receive liquid hydrocarbons or other liquid fuel 11, the whole being covered with a metallic cover 12 which is provided with an opening having a flange 14. This opening is preferably circular in form and is adapted to receive and support the sleeve 15 which is shown as a tapered tubular and cylindrical structure having a bead 16 adapted to rest upon the upper edge of the flange 14 and of such length as to extend close to the bottom 17 of the fuel receptacle. This sleeve 100 is provided with a plurality of rows of apertures 18 and 19, four being shown of circular configuration in a lower row, the lower row being a slight distance below the top of the cover 12 and of sufficient size to freely allow the burning and unconsumed gases to pass therethrough from the receptacle 5. The upper row 19 are elongated slots annularly disposed close to the top edge of the sleeve and are provided to register with 110

similarly shaped slots formed in the burner stack and admit air. Revolubly mounted within this sleeve is the burner or stack 21 of tubular construction and tapered on the 5 same taper as the sleeve 15, these members being preferably tapered so that they will nest or pack easily for shipment, the upper portion being provided with a plurality of rows of apertures 22, 23 and 24 preferably placed in parallel transverse planes, the two lower series being of similar shape and of the same size as the openings 19 and 18. Preferably disposed above the row of apertures 23 is a bead 25 which provides a support for the burner upon the rim of the 15 sleeve 15, the portion of the burner below this bead projecting within the sleeve 15 and forming slidable contact therewith, there being a second bead 26 preferably 20 formed in the burner stack below the series of orifices 24 formed therein which are shown and preferably of the same size and adapted to register with the openings 18 in the sleeve 15. The bead 26 is adapted to 25 space the burner a distance from the inner periphery of the sleeve 15 so that the burner may readily turn in relation to the sleeve and for this purpose a handle 27 is secured by suitable fastenings to the outer periphery 30 of the burner just above the bead 25.

In the modification shown in Fig. 3 a stack is shown as formed of two parts, the upper part 28 engaging with the flange 29 on the cover 30 which supports the inner 35 sleeve of similar configuration to the sleeve 15 shown in Fig. 1 and within this sleeve a stack extension 31 is provided having a bead 32 and an orifice 33 registering with the orifice 18 in the sleeve 15. The stack extension 31 is also provided with a flange 34 which rests upon the flange 16 of the sleeve 15, the stack extension 31 being adapted to be turned to position the openings 33 in any desired relation to the openings 18, a handle 40 45 35 being secured to the flange 34 by means of fastenings 36, the handle extending through a suitably disposed slot 37 cut in the burner top 28.

In the modification shown in Fig. 4 the 50 receptacle is shown as circular in plan, this receptacle 40 having openings 41 therein for the admission of air, a combined shield and cover 42 being shown, the cover portion having an opening provided with a flange 43 55 concentrically arranged therein, and the shield portion 44 being carried down into engagement with the receptacle to a point where a bead 45 is formed upon the walls of the receptacle, and the shield walls are bent 60 inwardly and then downwardly to form with the wall of the receptacle a chamber, the shield portion being provided with parallel rows of apertures 46. A number of these rows are formed on the shield projecting 65 below the level of the fuel therein, and

as these openings are uncovered the air is admitted direct and adjacent to the upper surface of the fluid fuel. The flange 43 is provided with an angle slot 47 which is adapted to receive a pin 48 mounted upon the sleeve 49 similar in form to the sleeve 15, provided with a number of rows of apertures which are adapted to register with a similar row of apertures formed in the stack burner 50, this burner being similar in form to the stack 21 provided with a fixed handle 51 shown as formed out of wire which completely encircles the burner above the supporting bead 52 which bears upon the flange 53 of the sleeve. 70 75 80

In Fig. 5 is shown the adaptation of the inner partitions similar to the shield 44, the walls 55 being spaced a sufficient distance from the end walls and a portion of the side walls so that air entering the openings 10 in the casing is distributed downward through the chamber and enters the openings 56 most adjacent to the top surface of the oil. Immediately opposite the burner stack and its connections the inner wall 55 85 is left out. The wall 55 has a flange 57 which rests upon the upper rim of the receptacle 5. 90

The operation of the burner will be readily understood, the fuel 11 being ignited 95 within the burner, air with oxygen therein enters through the openings 7 and 10 to mix with the heated gases which escape from the receptacle through the regulated openings 18 and 24 in the burner stack 21 where more air is admitted through the apertures 23 and 22 and by turning the stack a perfect regulation is effected thereby providing a perfectly clean blue flame and the entire fuel contents are consumed. 100 105

What I claim is:

1. An orchard heater, comprising a receptacle provided with draft openings, an apertured cover therefor, a sleeve having openings adapted to fit within the aperture in said cover, and a burner stack having openings adapted to be supported within said sleeve, the openings in the inclosed portions of the sleeve and stack adapted to be brought into or out of register. 110 115

2. An orchard heater, comprising a receptacle having draft openings therein and an opening in the cover thereof, an apertured sleeve supported within said opening in said cover and projecting within said receptacle, a turnable and apertured burner stack within said sleeve and adapted to be rotated therein to have certain of its apertures register with the apertures in said sleeve. 120 125

3. An orchard heater, comprising a metallic fuel receptacle having a plurality of draft openings disposed above the normal fuel line within said receptacle, an apertured cover therefor having a flange, a sleeve of tubular form supported in said 130

- flanged aperture of said cover and projecting within the fuel within said receptacle and having a plurality of openings in its walls, a tubular burner stack having a plurality of rows of openings therein adapted to fit within said sleeve and project upwardly therefrom, certain of said rows of openings registering with the apertures in said sleeve, and means to move said burner stack in relation to said sleeve to regulate the passage of gases through the registering rows of openings.
4. An orchard heater, comprising a fuel receptacle provided with draft openings, an apertured cover therefor, a sleeve adapted to fit within said apertured cover and extending above and below the aperture in said cover and having a plurality of openings within the receptacle, and a burner stack adapted to fit within said sleeve having a plurality of openings adapted to be brought into and out of registration with the before-mentioned openings in the sleeve to regulate the passage of gases from without the stack in the receptacle into the burner stack, and a row of openings in the sleeve without the receptacle, and a row of openings in the stack without the receptacle adapted to be brought into and out of registration to regulate the passage of air into the stack from without the receptacle.
5. An orchard heater, comprising a receptacle having draft openings therein and an opening in the cover thereof, an apertured sleeve supported within said opening in said cover and projecting within and without said receptacle, and an apertured burner stack adapted to fit within said sleeve and be moved therein, arranged to have certain of its apertures register with the apertures in said sleeve.
6. An orchard heater, comprising a metallic fuel receptacle having a plurality of draft openings disposed above the normal fuel line within said receptacle, an apertured cover therefor having a flange, a tubular sleeve supported in said flanged aperture of said cover and projecting into the fuel and within and without said receptacle and having a row of openings in its walls within the receptacle and a row of openings without the receptacle, a tubular burner stack having a plurality of rows of openings therein adapted to fit within said sleeve and project upwardly therefrom, one of said rows of openings registering with the apertures in said sleeve without the receptacle and another of said rows of openings registering with the apertures in the sleeve within the receptacle and means to move said burner stack in relation to said sleeve to regulate the passage of gases from within the receptacle through the registering rows of openings into the burner stack, and also the regulation of the air entering the stack through the openings from without the receptacle.

In witness that I claim the foregoing I have hereunto subscribed my name this 15th day of October, 1913.

CHARLES D. FILSTEAD.
